[57] CLAIM

The ornamental design for a chair, as shown and described.

DESCRIPTION

FIG. 1 is a left-front perspective view of the chair showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a left-front perspective view of a second embodiment of the chair, the sole difference being in a higher backrest; and,

FIG. 9 is a left-front perspective view of a third embodiment of the chair, the only differences being the extended pedestal and a footrest.

The fragmented cross-hatching on the seat and backrest is understood to represent fabric which would be continuous throughout the implied areas.
